JOHN C. CLASEN

John H. Brumming.
His Attorney.

UNITED STATES PATENT OFFICE.

JOHN C. CLASEN, OF ST. LOUIS, MISSOURI, ASSIGNOR, BY MESNE ASSIGNMENTS, TO CLASEN NATUREPHONE COMPANY, OF WILMINGTON, DELAWARE, A CORPORATION OF DELAWARE.

SOUND REPRODUCING OR RECORDING MECHANISM FOR PHONOGRAHS.

Continuation of application Serial No. 445,927, filed February 18, 1921. This application filed August 1, 1921. Serial No. 488,894.

To all whom it may concern:

Be it known that I, JOHN C. CLASEN, a citizen of the United States, and residing at St. Louis, Missouri, have invented the 5 new and useful Improvement in Sound Reproducing or Recording Mechanism for Phonographs, of which the following is a specification.

This invention relates to phonographs, 10 and more particularly to the sound recording and reproducing mechanism thereof. This application is a continuation of application Serial Number 445,927, filed February 18, 1921, as to common subject matter.

15 As is well known a phonograph is a device for recording or reproducing sounds. Great difficulty has been experienced in the past in reproducing sounds with exact accuracy. In order to accomplish such a result, the vibrating parts of both the recording and reproducing apparatus must be so designed and constructed that they will follow accurately all of the undulations by which such sound is rendered audible. As 20 the so-called wave-shape of the undulations corresponding to certain sounds, particularly those produced by the human voice, are very complex, it has been practically impossible to construct apparatus which will follow such complex vibrations with great accuracy.

25 One of the objects of this invention, therefore, is to so improve the phonograph mechanism that sounds may be recorded and reproduced with greater accuracy.

30 Further objects will appear from the detail description taken in connection with the accompanying drawing, in which:

Figure 1 is a longitudinal vertical section of the reproducing mechanism embodying this invention;

Figure 2 is a section on line 2—2, Figure 1, showing the entrance element to the tone arm; and

Figure 3 is a detail perspective view of the same.

Referring to the accompanying drawing 1 designates a base which is provided with a hub 2 which is formed to receive a tubular part 3 adapted for connection to a tone arm. The parts 2 and 3 are secured together by a

ring 4 clamped on the hub 2, the part 3 having a flange 5 which is mounted between a pair of rubber rings 6 in order to secure the parts together. A diaphragm 7 is 55 clamped to the base 1 by a ring 8 and between a pair of rubber rings 9. A lever is pivoted at 10 on the ring or on the base and has an arm 11 connected with the diaphragm while the other arm 12 of the lever has a 60 socket to receive a needle or stylus 13 which is clamped therein by a screw 14. The structure so far described may be the usual one employed in reproducers and a detail description thereof is, therefore, unnecessary. 65

The diaphragm 7 is, in accordance with this invention, constructed of horn since it is found that the recording or reproduction of the sound can be accomplished with much 70 greater accuracy when made of that material than with the diaphragms at present in use, as it is found that such a diaphragm follows the sound vibrations with greatly improved accuracy without introducing any 75 new vibrations or modifications of its own. This horn must, however, be prepared in a particular manner and in accordance with a particular process and must have certain characteristics. A detail description of the 80 process will, therefore, be given.

In preparing the diaphragm it is found that a cattle horn gives the best results and the central strata or core of the horn structure at that should be used. In accordance 85 with this invention, therefore, the cattle horn is boiled in water and then is pressed flat. The outside surfaces are then shaved off, leaving the inside core. This core can then in turn be split into portions about one-thirty-second of an inch in thickness. Out of this the diaphragms can be cut to a suitable size. These diaphragms are then polished by any suitable abrading or polishing material and are then dipped in boiling 90 mineral oil; they are then ironed either with flat irons or by passing through hot rolls. The effect of this dipping in oil, ironing and other treatment is not only to condense the material but also to harden and temper the 95 diaphragm, giving it the desired homogeneous structure, resiliency and polished and 100

hard surfaces. It will be understood, of course, that this entire procedure may be performed on the stock before the diaphragms are cut therefrom.

5 The completed diaphragm is mounted in position and can be secured to the arm 11 by an adhesive 15 which may be a composition of wax and rosin. If desired, a screw 16 may be used as a supplemental fastening although this is unnecessary as that particular cement will adhere closely to the horn.

10 The entrance from the diaphragm chamber to the tone arm is provided with a bushing 17 which is also constructed of horn formed to shape. This bushing may be cut from the tip of the horn and is polished and dipped in hot mineral oil to harden and temper the same as in the case of the diaphragms. This bushing projects into the part 3 connected with the tone arm and forming the tone chamber and the projecting portion is reduced in diameter as shown at 18 and is provided with perforations 19 and with a cut-away 20.

15 It is found that a reproducer constructed as described will attain the objects of this invention. Not only will the diaphragm accurately record and reproduce the sound vibrations with greatly improved accuracy, but without introducing any new vibrations or modifications of its own. Accordingly all metallic sounds are avoided and it is particularly adapted for recording and reproducing high notes and peculiar notes, such as of 20 string and wind instruments. The action of the entrance element 17 is to improve reproduction since it not only avoids external vibration but seems to direct the sound waves in such a manner as to secure not only accurate reproduction but also so as to avoid all metallic sounds.

25 It is obvious that various changes may be made in details without departing from the spirit of this invention; it is, therefore, to be understood that this invention is not to be limited to the specific details shown and described.

Having thus described the invention, what is claimed is:

1. In an amplifying reproducer of music, 50 a diaphragm of tempered horn.
2. In an amplifying reproducer of music, a diaphragm of condensed horn.
3. In an amplifying reproducer of music, a diaphragm formed of the core of a horn. 55
4. In an amplifying reproducer of music, a diaphragm formed of the tempered core of a horn,
5. In an amplifying reproducer of music, a diaphragm formed of the condensed core of 60 a horn.
6. In an amplifying reproducer of music, a diaphragm of ironed horn.
7. In the art of making diaphragms of horn, the step comprising, condensing the 65 horn.
8. In the art of making diaphragms of horn, the step comprising, ironing the horn.
9. In the art of making diaphragms of horn, the step comprising, treating the horn 70 with oil.
10. In the art of making diaphragms of horn, the step comprising, treating the horn with oil, and ironing the treated horn.
11. In the art of making diaphragms of 75 horn, the step comprising, removing the outer surfaces of the horn, and polishing the core.
12. In the art of making diaphragms of horn, the step comprising, removing the outer surfaces of the horn, and condensing the core.
13. In the art of making diaphragms of horn, the step comprising, removing the outer surfaces of the horn, and treating the 80 core with oil.
14. In the art of making diaphragms of horn, the step comprising, removing the outer surfaces of the horn, treating the core with oil, and ironing the treated core. 90

In testimony whereof I affix my signature this 20th day of July, 1921.

JOHN C. CLASEN,
